UNITED STATES PATENT OFFICE.

ERIK O. ROED, OF PHILADELPHIA, PENNSYLVANIA, ASSIGNOR OF ONE-HALF
TO DAVID SCANNELL, OF SAME PLACE.

FIRE-ESCAPE LADDER.

SPECIFICATION forming part of Letters Patent No. 364,546, dated June 7, 1887.

Application filed October 12, 1886. Serial No. 216,007. (No model.)

To all whom it may concern:

Be it known that I, ERIK O. ROED, a citizen of the United States, residing at Philadelphia, in the county of Philadelphia and State 5 of Pennsylvania, have invented certain new and useful Improvements in Fire-Escape Ladders; and I do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 My invention relates to that class of fire-escapes which consists of a folding ladder, one upright of which is secured within a channel formed upon the exterior of the building, while the other upright is adapted to swing down- 20 ward and away from the fixed upright to open the ladder, the rounds or rungs being pivoted to both uprights, and to be operated or moved in a reverse direction for closing the ladder.

The invention also consists in the combination, 25 with the folding ladder, of novel means for retaining it folded and unfolding the same, whereby the ladder can be successfully operated within the room upon any story of the building to which it is attached.

30 In the accompanying drawings, in which corresponding parts are designated by similar letters, Figure 1 represents a side elevation of the ladder unfolded, one upright being attached to a mortise in the wall, and having my im- 35 provement applied thereto. Fig. 2 represents a wall in section with the ladder and lever mechanism for holding and unlocking the same applied thereto. Fig. 3 is a detail view of the lever mechanism, and Fig. 4 a front elevation 40 of the bracket used at the head of the ladder.

Referring to the drawings, A represents the wall of building, having a channel, *a*, which travels the same from top to bottom, for the reception of the ladder.

45 B designates the stationary or fixed upright, secured to the wall by bolts or otherwise.

B' designates the movable upright, which consists of a channel-iron of proper size, to which the rounds are bolted or pivoted within 50 said channel, and extend parallel to one an-

other across and pivoted to the opposite upright or stationary standard secured to the exterior of the building, which rounds or rungs *b* form or afford resting places and steps by which persons may pass from the windows of 55 a building to the ground, when the movable upright B' is thrown down, but when not in use, can be readily swung upward and close to the wall.

To the top of the building are secured two 60 screw-eyes, *c c*, which receive the ends of the hinged bracket C, and adapted to move outward and upward with the movable upright by being hinged to the upper end of the same, for the purpose of supporting and affording 65 perfect movement to the ladder when being operated.

Through the wall of the building opposite to the ladder, and upon each floor of the same, is an opening through which the lever mechanisms are inserted and fastened. The lever mechanism is composed of two arms at right angles to one another, the upright arm *d* being provided with a handle for the purpose of throwing the said arm to and from the interior 75 of the wall of the building. The opposite extension, *d'*, is inserted in the recess cut through the wall and pivoted. The horizontal arm *d'* of the lever mechanism D is provided with a slot, which comes flush with the exterior of the 80 building, for receiving pins *e*, secured to the bar E, and also with hook *e'*, formed upon its end, for receiving pins or projections extending from the rounds secured to the movable upright.

In carrying out my invention it will be observed that the entire operation of the ladder can be successfully operated within any room traversed by the ladder, by pulling down the same. Thus, when the upright extension of the 90 lever mechanism is thrown down, it releases the hook formed upon the end of the horizontal arm, and at the same time raises the bar E, which releases the remaining locks as perfectly as if operated directly by the operator, thereby 95 making an automatic and reliable fire-escape in every respect.

I do not claim, broadly, a folding fire-escape ladder composed of a fixed upright, a movable upright, and rounds pivoted in both said up- 100

rights, one or both of the uprights being recessed on their inner or adjacent sides to receive the said rounds when the movable upright is swung upward against the fixed upright, and mechanisms for operating the same in a horizontal or closed position.

What I claim as my invention, and desire to secure by Letters Patent, is—

1. The combination, with a building, of the folding ladder, one upright of which is secured within a channel secured to the exterior of the building, and the other of which is movable downward and outward from the building, the angular lever extending through the wall and provided with a hook for receiving pins or projections secured to the movable upright,

and the bar E, carrying pins which receive the slot in the horizontal arm of the lever, as and for the purpose described.

2. In a fire-escape ladder, the lever D, pivoted in the wall and provided with the slot which receives the pins or projections e, secured to the releasing-bar E, and the hook e', for receiving the pins, secured to the movable upright, as and for the purpose described.

In testimony whereof I affix my signature in presence of two witnesses.

ERIK O. ROED.
